CLAIM

The ornamental design for an adjustable raised dog bowl, as shown and described.

DESCRIPTION

FIG. 1 is a front, right and top perspective view of an adjustable raised dog bowl, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is another front, right, top perspective view, but shown in a folded position of use for clarity of illustration; and,

FIG. 10 is an exploded perspective view thereof, shown disassembled for completeness of illustration.

The broken lines depict portions of the adjustable raised dog bowl that form no part of the claimed design.
